UNITED STATES PATENT OFFICE

JOHN H. SPOHN, JR., OF SAN FRANCISCO, CALIFORNIA

BOTTLE FOR CONTAINING FLUIDS

Application filed July 25, 1927. Serial No. 208,105.

My invention relates to containers, and particularly to a bottle for use with fluids which are removed from the bottle in small amounts at different times.

5 An object of my invention is to provide a bottle in which fluid flowing over the outlet will not run down the sides of the bottle wasting the liquid and presenting an unsightly appearance.

10 My invention possesses other advantageous features, some of which with the foregoing, will be set forth at length in the following description where I shall outline in full that form of the bottle of my invention, which I 15 have selected for illustration in the drawings accompanying and forming part of the present specification. In said drawings I have shown one form of bottle embodying my invention, but it is to be understood that I do 20 not limit myself to such form since the invention as set forth in the claim may be embodied in a plurality of forms.

In the drawings:

Fig. 1 is a side elevation of one modification of the bottle of my invention, a portion of the outside housing being broken away to disclose the interior.

Fig. 2 is a transverse section of the form of container shown in Fig. 1.

30 Fig. 3 is a transverse section similar to Fig. 2, but showing a modified form of bottle of my invention.

Fig. 4 is a bottom view of the closure for the bottle of my invention.

35 Preferably included in the bottle of my invention are a container having a reduced neck and provided with a wall spaced from the neck and joining to form a cup, together with a closure which seals both the container and the cup.

40 My invention is well adapted for use with a variety of liquids, such as syrups and so forth, but it finds a particularly apt use in connection with shoe polish. Liquid shoe polish is usually furnished in a glass bottle having a dauber affixed to the bottle stopper for applying the liquid polish to shoes. The dauber is withdrawn from the bottle and is usually scraped over the edge of the neck of 45 the bottle in order to remove surplus liquid

polish therefrom. Some of the surplus polish finds its way down the exterior of the bottle rendering the bottle unsightly and difficult to handle. A good portion of the polish is also wasted by this method and is likely to 55 come into contact with foreign substances and soil them.

The modification of my invention disclosed in Figs. 1 and 2 comprises a container 6 usually of glass or similar material which is of the usual contour and is narrowed or reduced at its upper portion to form a neck 7 surrounding the outlet 8. The neck of the bottle is preferably threaded as at 9 to cooperate with a closure 11. The closure can be of any 60 preferred form and in the present instance comprises a metallic cap 12 provided with a liner 13 of yielding material to make a liquid tight seal with the outlet. The metal cap 12 is threaded to engage threads 9 and effectively 65 prevents leakage of the liquid within the 70 container 6.

The metallic cap is firmly embedded in a handle portion which can conveniently be made of wood shaped for easy manipulation. 75 Passing thru the cap 12 and seated in the closure 11, is a barbed rod 14 extending axially into the container 6. At its lower end, the rod carries absorbent material 16 formed into a ball to act as a dauber. Upon removal of the closure 11, the dauber 16 is removed from the liquid within the container 6 and can be applied to the surface to be treated. Replacement of the closure returns the dauber 80 to the liquid, preparing it for the next application and also effectively seals the liquid from contact with air. 85

Means are provided for preventing liquid overflowing the edge of the outlet 8 from running down the outside of the bottle and thereby spoiling its appearance and making it difficult to handle. The entire container 6 is fitted tightly into a surrounding housing 17 preferably of treated fiber board or paper 90 board of cylindrical shape and extending from the bottom of the container 6 where it is sealed by a cup 18 of comparable material, to the top of the bottle adjacent the neck 7. The housing 17 is preferably concentric with 95 100

the neck 7 although it generally is of lesser height.

The closure 11 is preferably extended peripherally to overlie the upstanding wall 5 formed by the housing 17 and can be provided with a peripheral groove 19 to cooperate with the upstanding wall of the housing 17 to provide a tight seal. In this form of the invention, when the dauber 16 is scraped 10 across the upper edge of the neck 7, any liquid which ordinarily would run down the outside of the bottle falls into the cup-like annular depression formed between the exterior of the neck and the interior of the 15 housing 17 and is caught. It is sealed from the atmosphere by the closure 11 which also closes the outlet 8, and the entire bottle can then be packed and shipped without danger of losing any of its contents. The exterior 20 of the casing 17 is always clean and easily handled while less care is needed in rubbing the dauber over the neck of the bottle to remove surplus fluid or liquid therefrom.

In the modified form of the invention disclosed in Fig. 3, instead of providing a separate housing 17, the container 21 is formed with a restricted neck 22 as before, but is also formed with an integral upstanding wall 23 forming a cylindrical collar concentric with 25 the neck 22 to provide a cup 24 therebetween. A closure 11 is provided for the cup 24 and also for the outlet of the container.

In either form of my invention, a slightly 30 container for fluid is provided in which no liquid is permitted to run over the outside of the container where it can cause damage to other articles and be a nuisance generally.

I claim:

A bottle for containing liquids comprising 35 a container having a cylindrical neck, threads on said neck, a cylindrical wall spaced from said neck and joined to said container to form a cup, a closure for said container and said cup comprising a cap adapted to engage the 40 threads on said neck to seal said container, and a handle secured to said cap, said handle having an annular fillet portion depending into said cup and engaging said container 45 whereby said cup is sealed simultaneously 50 with the sealing of said container.

In testimony whereof, I have hereunto set my hand.

JOHN H. SPOHN, JR.
